United States Patent Office.

JAMES S. ATTERBURY AND THOMAS B. ATTERBURY, OF PITTSBURG,
PENNSYLVANIA.

Design No. 4,915, dated May 16, 1871.

DESIGN FOR A JELLY-GLASS.

The Schedule referred to in these Letters Patent and making part of the same.

To all whom it may concern:

Be it known that we, JAMES S. ATTERBURY and THOMAS B. ATTERBURY, of Pittsburg, in the county of Allegheny and State of Pennsylvania, have invented and produced a new and original Design for a Jelly-Glass, of which the following is a description.

The side elevation of the jelly-glass represented in the accompanying drawing fully illustrates the nature of our design.

The form of the glass is that of the frustum of a paraboloid, *a a* being the sides and *b* the bottom.

We claim as our invention—

The design for a jelly-glass, as shown.

JAMES S. ATTERBURY.
THOMAS B. ATTERBURY.
